INVENTOR

Thomas Farmer Jr.

UNITED STATES PATENT OFFICE.

THOMAS FARMER, JR., OF NEW YORK, N. Y., ASSIGNOR TO CONSOLIDATED CAR-HEATING COMPANY, OF ALBANY, NEW YORK, A CORPORATION OF WEST VIRGINIA.

DOOR-GUARD.

1,247,653.

Specification of Letters Patent. Patented Nov. 27, 1917.

Application filed August 13, 1914. Serial No. 856,704.

To all whom it may concern:

Be it known that I, THOMAS FARMER, Jr., a citizen of the United States, residing at New York city, borough of Manhattan, 5 county of New York, State of New York, have invented certain new and useful Improvements in Door-Guards, the following being a full, clear, and exact disclosure of the one form of my invention which I at 10 present deem preferable.

For a detailed description of the present form of my invention, reference may be had to the following specification and to the accompanying drawing, which illustrates my 15 invention.

My invention relates to a safety device for preventing injury to a person in a doorway by a motor-operated door. It has been proposed to place on such a door a yielding 20 guard or fender which will act to stop the progress of the door when it comes in contact with a person or other obstruction in the doorway. It is, however, desirable that the door should not only be stopped, but also 25 opened or drawn back in such a contingency, and I make provision for that by mounting a yielding guard on the jamb or frame of the door in an exposed position, so that in the contingency mentioned, the guard will be 30 pressed inward and thereby caused to operate the reverser of the door-motor which will then draw back or open the door. I also provide that the said guard, which is necessarily exposed to contact with a person 35 in the doorway, will be disabled, so long as the door is shut, so that it cannot be used at that time as a means for unauthorized opening of the door.

Referring to the drawing, A represents a 40 door, B a pneumatic motor therefor and C an electromagnetic controlling valve therefor. These are of a well known type which does not call for description, it being noted that the magnet c^1 , in circuit 5 of the con- 45 troller, is the one which acts to cause the door-opening movement and c^2 , in circuit 6, the one which acts to cause the door-closing movement, the magnets are normally controlled by the push-buttons a and b at the 50 point of operation by the traumman. G represents the guard which is a vertical strip flexibly mounted on the door-frame or jamb at one side of the line of travel of the door so as to be exposed to contact with a person 55 in the doorway who might be caught be-

tween the jamb and the door when the latter is being closed by the motor. The guard G when it yields acts to close one or both contacts 1 and 2 which serve to close a controlling circuit 5^a leading to the door-opening magnet c^1 . In this circuit 5^a and in series with contacts 1 and 2, I place a spring switch 4 that makes contact with point 3 to maintain the continuity of the said circuit at all times except when the door is closed. 60 As the door approaches its closed position, a projection E thereon engages switch 4 and draws it away from point 3 to break circuit 5^a at that point and maintain it broken until the door again opens. By this means I 65 prevent the unauthorized use of the yielding and exposed guard G as a circuit-closer for the door-opening magnet c^1 , so long as the door is closed. When the door is still open, however, a person or object in the doorway who may be pressed against the guard G by the force of the motor will cause the guard to yield thereby closing circuit 5^a and reversing the motor to draw the door back 70 toward its open position. 75

When the circuit is closed by the button a the current travels from the battery through wire 5 to the magnet c^1 and from thence to ground, said magnet operating the valve to introduce fluid pressure in the motor B in 80 such manner as to open the door. When the circuit is closed through button b the current passes from the battery through wire 6 to the magnet c^2 and from thence to ground, the action being to close the door. Assuming the switch 4 to be in engagement with the contacts 3, when the circuit is closed at 85 1 or 2 by the movement of the guard, the current passes from the battery, to the contacts 1 and 2, from thence to the contact 3, switch blade 4, wire 5^a, and wire 5 to the magnet c^1 and thence to ground, reversing the motor to open the door, and shunting the current from magnet c^2 . 90

What I claim as new and desire to secure 100 by Letters Patent is:

1. The combination with a door, and a motor for operating the same, of an electro- 105 magnetic device for controlling said motor, a guard movably attached to said door, a circuit for said electromagnetic device, a branch circuit controlled by said guard and shunting a portion of said electro-magnetic device, a switch controlling said branch circuit, and means attached to said door for 110

moving said switch when the door reaches a predetermined position.

2. The combination with a door, and a motor for operating the same, of an electro-magnetic device for controlling said motor, a guard movably attached to said door, a circuit for said electromagnetic device, a branch circuit controlled by said guard and shunting a portion of said electro-magnetic device, a switch in said branch circuit provided with a spring pressed blade positioned

to normally close the circuit, and a trip member attached to the door and positioned to engage said switch blade to open the circuit as the door approaches closed position. 18

In witness whereof I have hereunto set my hand, before two subscribing witnesses, this 12th day of Aug., 1914.

THOMAS FARMER, Jr.
